HIGHWAY GUARD

Walter F. Schulz, Youngstown, Ohio, assignor to
 Truscon Steel Company, Youngstown, Ohio, a
 corporation of Michigan

Application November 2, 1935, Serial No. 48,011

10 Claims. (Cl. 256—13.1)

This invention relates to an impact absorbing member adapted to be used singly or in multiple as a guard rail wherever automotive vehicles may be used or stored to minimize property damage.

To that end the invention contemplates a novel guard strip having special features of construction which render the same of special utility in garages; at bridge approaches and also in highway guards of the type used at curves, embankments, and other points of traffic hazard along the highway for preventing vehicles from leaving the road.

Highway guards utilizing a guard strip of sheet steel have many advantages over other types of road guards, not only from the standpoint of manufacture and assembly, or erection, but also from the standpoint of strength, durability and the facility with which they may be repaired in case of extraordinary damage. In that connection, one of the important considerations is to provide a sheet steel strip which will not only readily yield under impact but will also deflect the vehicle back to a position or course of safety and at the same time return to normal position after the blow has been delivered. Various expedients have been heretofore resorted to for tensioning a strip or guard rail either between individual posts or between the end posts or so-called "dead-men". While these types of devices are more or less efficient and reliably function under the most rigid service conditions, nevertheless, it is desirable to simplify the construction not only to effect greater economy in manufacture but likewise to save labor and material in installation.

Accordingly, the present invention has primarily in view, a simple and practical type of guard strip which may be mounted on suitable supports, and which has the distinctly advantageous feature of carrying therewith its own tensioning means so that it may not only more adequately absorb the shock of impact but will more quickly and effectively recuperate after being subjected to a blow. In its general aspect, the invention includes a guard strip having an offset tensioning portion or portions which tend to elongate when the face of the strip is subjected to impact, thereby not only permitting the strip to quickly yield, but at the same time placing the said laterally projecting portion under increasing tension so that after the load or impact has been removed, the body of the strip will be quickly brought or drawn back to normal condition.

A further object of the invention is to provide a guard strip having an integral tensioning portion which has the advantage of enabling the tensioning means to be incorporated in the strip by subjecting the same to a simple mechanical operation which gives the offset portions of the strip the desired set to pre-dispose the metal thereof in such a way that the deformations tend to flatten out when the strip is subjected to impact, thereby placing the deformed portions under tension which will cause the strip to quickly recuperate when the force of the impact is relieved.

A further object of the invention is to provide a guard strip which has a greater elastic limit than a flat strip, thereby avoiding rupture under extraordinary impact while at the same time tending to bring the strip back to normal condition as previously indicated.

With the above and other objects in view which will more readily appear as the nature of the invention is better understood, the same consists in the novel features of construction, combination and arrangement of parts as will be hereinafter more fully described, illustrated in the accompanying drawings and defined in the appended claims.

A preferred and practical embodiment of the invention is shown in the accompanying drawings, in which:

Figure 1 is a top plan view of a strip embodying the present improvements used in a highway guard.

Figure 2 is an enlarged detail elevation of a pair of interconnected strips.

Figure 3 is a top plan view of the construction shown in Figure 2.

Figure 4 is a vertical cross-sectional view taken on the line 4—4 of Figure 2.

Figure 5 is a detail perspective view of a portion of the strip looking at the same from the rear.

Figure 6 is a diagrammatic view illustrating the manner in which an installed strip yields or deflects under impact.

Figure 7 is a diagram illustrating the normal set position of the spring sections forming the sinuous tensioning member.

Figure 8 is a diagram illustrating the manner in which the spring sections tend to flatten out under stress.

Similar reference characters designate corresponding parts throughout the several figures of the drawings.

According to the example chosen to illustrate

the application of the invention to one of its uses, the novel strip sections A are shown as interconnected to provide a continuous guard rail whose opposite ends are anchored as at B to the end 5 posts or dead men C while the intermediate portions of the rail, composed of the several strips, are supported by the posts D and the brackets E. The brackets E may be of any suitable type, such for example as that shown in my copending application Serial No. 25,491, filed June 7, 1935 and the end strip of the rail may be secured to the end posts C by suitable tie rods C' without the necessity of using coil or other springs since each individual strip comprising the rail embodies 10 or includes its own tensioning means, and the entire installation is originally set up under tension throughout, that is from one extremity to the other.

The brackets E on intermediate posts preferably include yielding arms for supporting the strip and the entire bracket is so mounted on the post as to have a limited shiftable or sliding movement in a horizontal direction across the face of the post not only to better adjust the 15 strip to change in length due to temperature variation but also to assist in distributing the force of the impact throughout the rail and to the end posts.

Referring particularly to the individual strips, 20 it will be observed that each includes a body portion 1 which presents a smooth outer impact face intended to be disposed toward the approaching vehicle while a portion of the strip is offset or deflected rearwardly to provide the tensioning 25 flange 2. In the example shown, the strips are provided with opposite tensioning flanges extending along the margins of the strip so that the entire strip partakes of a channel shaped formation as will be apparent from Figure 4. The 30 tensioning elements 2 are preferably formed integrally with the body 1 and consist of a plurality of arched deformations 3 which constitute a plurality of individual spring tensioning sections extending throughout the length of the strip. In 35 practice, the strip is formed into substantially channel shape to provide the offset flanges 2 and then the flanges are subjected to a deforming operation by means of rolls or dies while the metal is either hot or cold to produce the sinuous 40 flange formations including the preformed individual spring sections referred to. By deflecting the metal of the flanges into the arched or substantially fluted formation shown, it will be apparent that each section will have a tendency to 45 normally assume the arched or bowed formation referred to, but when the body 1 of the strip is subjected to impact, thereby to become flexed on an arc between the brackets or supports, the 50 spring sections 3 will yield along with the body 55 of the strip and tend to flatten out; but, because they are in tension when under stress, as soon as the force of the impact is removed, the plurality of spring sections will tend to contract and thus 60 pull the body of the strip back to normal position. 65 Moreover, while the strip is being subjected to impact, it will be apparent that the various spring sections give added resiliency or strength to the strip tending to counteract the force of the impact and push the vehicle back to safety.

70 In assembling the strips into guard rail formation, the end portions are placed in substantially telescopic relation so as to overlap preferably in the location of the brackets E. Both ends of each strip are provided with spaced pairs of longitudinally oval openings 4-4 which may be

brought into registry to receive the bolts or fastenings 5 for not only interconnecting the strips but also mounting them on the brackets. The purpose of the oval or elongated holes 4 is to permit sufficient tolerance in a vertical direction 5 to enable the interconnected strips to assume a relatively angular relation in a general horizontal direction to permit the rail to follow the undulations of the roadside.

The last strip in the rail, that is the strip in each end thereof, may have its outer extremity equipped with a channel or equivalent member 6, preferably perforated at suitable locations to receive the tie rods C' which are connected to the end posts as previously referred to. When the strips are assembled in guard rail formation and installed for service, all of the strips constituting the guard rail are placed under tension from the end posts. In other words, the entire guard rail comprising the interconnected strips A is placed 20 under tension by tightening the nuts on the tie rods C so that the entire guard rail assumes the characteristics of continuous elastic band. When the installation is made, due consideration is given to the temperature conditions prevailing 25 at the time, the original tension being sufficient to take care of average seasonal temperature variations and consequent variations in the length of the strip. Roughly, the strips of the individual guard rails are tensioned originally between 30 20,000 lbs. and 40,000 lbs., proper tolerance being calculated for low temperature conditions when the sheets are under increasing stress due to contraction and for temperature conditions prevailing 35 in summer when the sheets forming the strips are reduced in stress. Therefore, under standard 40 conditions of installation, the entire strip is always under tension from end to end, or in other words is always stretched or elongated, not only to provide for changes in length of the strip due to 45 temperature changes, but also to provide rebound or reflex resilience responsive to impact.

When the individual strips are subjected to impact, they will yield, according to the force of the impact on an arc of relatively long radius because 45 the supporting posts are usually placed on an average of sixteen feet apart. Therefore, the vehicle will be deflected back to a safe position along a gradually curved surface due to the arc 50 of long radius previously referred to, generated at the time of impact. As the blow is delivered 55 to the individual strip, the individual spring sections are elongated in proportion to the intensity of the impact, the tensioning wave on the successive spring sections generating progressively from the body of the strip toward the outer edge portion of the flange 2. With the type of steel sheet 60 ordinarily used, the deflection of the strip may have an average maximum deflection of approximately 18 inches, but in every case, the structure is designed so that the yield point of the metal is not reached when the sinuous flange 2 is stretched to a substantially straight line.

From the foregoing, it will be apparent that the 65 present strip provides, in itself, an efficient elastic member constituting a guard having its own tensioning means, for example, the sinuous flange or flanges 2 whose individual sections store up energy when a blow is imposed on the strip due to being stretched, and which contract when the 70 blow or impact is relieved to return the stress back to normal position throughout its length. Moreover, due to the fact that with the present construction the strips can be made longer than ordinary strips because of their channel forma- 75

tion, which imparts a certain amount of stiffness without impairing resilience or flexibility in action, the supporting posts may be spaced further apart, thus effecting further economy in installation. Also, all coil springs and other separate spring devices are eliminated with a consequent elimination of cost.

Without further description it is thought that the features and advantages of the invention will 10 be readily apparent to those skilled in the art, and it will of course be understood that changes in the form, proportion and minor details of construction may be resorted to, without departing from the spirit of the invention and scope of the 15 appended claims.

I claim:—

1. A self-recuperating impact absorbing member adapted to be supported at its ends, including a metallic strip-like body having an impact 20 receiving face and carrying tensioning means bent backwardly from a longitudinal edge and effective on deformation of the body by a blow imposed on said impact receiving face between the ends of the strip to bring the body back to its 25 normal plane.

2. A self-recuperating impact absorbing member adapted to be supported at its ends, including a metallic strip-like body having an impact receiving face and carrying integral spring means 30 bent backwardly therefrom and effective upon deformation of the body by a blow imposed on the said impact receiving face to bring the body back to its normal plane.

3. A self-recuperating impact absorbing member adapted to be supported at its ends, including, a normally plane strip-like body having an impact receiving face and carrying an integral de- 35 formed elastic flange effective upon deformation of the body by a blow imposed on the impact face thereof to bring the body back to its normal plane.

4. A self-recuperating impact absorbing member adapted to be supported at its ends, including a metallic strip-like body having a normal plane 40 receiving face and also having a laterally project- 45 ing tensioning portion effective upon the deformation of the body by a blow imposed on the im-

pact receiving face thereof to bring the body back to its normal plane.

5. An impact absorbing guard comprising spaced supports and a yieldable guard strip carried by said supports and having a laterally projecting tensioning portion, said tensioning portion comprising a series of spring tensioning sections. 5

6. An impact receiving guard comprising spaced supports and a yieldable guard strip of 10 substantially channel shape cross section, the sides of the channel being deformed to provide a plurality of tensioning portions which elongate under stress due to impact imposed on the face of the strip and contract on removal of impact to 15 automatically return the strip to normal position.

7. A guard strip including a body having a front impact receiving face and integral self-adjusting continuous spring means at the rear face 20 of the strip. 20

8. A self-recuperating strip for highway guards and the like comprising a yieldable body having a portion projecting therefrom deformed to produce a series of spring tensioning sections of substantially arched formation, thereby providing an 25 elastic member whose total initial length is greater than the face of the strip, whereby when the latter is subjected to impact the spring sections will elongate and when impact is removed the sections will contract and the body of the strip 30 will return to normal position. 30

9. A highway guard comprising a plurality of interconnected strips each having individual continuous tensioning elements and forming a guard 35 rail, and means at the extremities of the guard rail for tensioning the same throughout its entire length.

10. A highway guard comprising a continuous elastic guard rail having an impact face and normally held throughout its entire length under 40 predetermined stress to provide tension for permitting the rail to expand and contract under varying temperature conditions and also having a continuous elastic flange portion at right angles to said impact face to provide reflex resilience 45 responsive to impact. 45
